UNITED STATES PATENT OFFICE.

MICHAEL HAWIE, OF GREENS FARMS, CONNECTICUT.

BUCKLE.

Application filed February 1, 1924. Serial No. 689,850.

To all whom it may concern:

Be it known that MICHAEL HAWIE, a citizen of the United States, and resident of Greens Farms, in the county of Fairfield 5 and State of Connecticut, has invented certain new and useful Improvements in Buckles, of which the following is a specification.

This invention relates to an improved 10 form of suspender buckle, and particularly that type of buckle known as "rustless back" buckles, an object of the invention being to provide a two-part buckle of this character, which will be simple in construction, effectual in operation, and which will present 15 a smooth surface free of any sharp or rough projections. A further object is to provide a buckle which will be relatively flat and thin, so that no perceptible bulge will be produced in the clothing of the wearer, and which will furthermore be comfortable in 20 use. Another object is to provide means by which the web may be securely fastened, without the necessity of stitching, and by 25 means of which an appreciable saving in web may be effected.

Still another object is to provide a two 30 piece buckle in which each piece will be formed from a single metal stamping, and including in one member an improved form 35 of pivotal bar formed integrally therewith, and in the other a coacting lever by means of which the web is clamped.

A still further object is to provide an improved 40 method of forming and assembling the buckle, to the end that the same will be economical to manufacture, durable in construction, effectual in operation and adapted to be used on both suspenders and hose 45 porters in the usual manner.

With the above and other objects in view, an embodiment of the invention is shown in the accompanying drawings, and this embodiment will be hereinafter more fully described with reference thereto, and the invention will be finally pointed out in the 50 claims.

In the drawings:

Fig. 1 is a front elevation of the buckle 55 and webbing, according to the present embodiment of the invention, and showing the buckle closed;

Fig. 2 is an edge view of the same;

Fig. 3 is a vertical sectional view, taken 55 along the line 3—3 of Fig. 1;

Fig. 4 is a front elevation of the buckle,

before attachment of the web, and with the lever member swung to full open position;

Fig. 5 is a side view of the same;

Fig. 6 is a front elevation of the buckle, 60 as shown in Fig. 4, and in the closed position of the lever member;

Fig. 7 is a side view of the same;

Fig. 8 is a front elevation of the frame member of the buckle before attachment of 65 the lever member thereto; and

Fig. 9 is a sectional view of the same, taken along the line 9—9 of Fig. 8.

Similar reference characters indicate corresponding parts throughout the several 70 figures of the drawings.

Referring to the drawings, the buckle according to the present embodiment of the invention is formed of two parts of sheet metal, and comprises a frame member and 75 a lever member, each of one-piece construction.

The frame member consists of a flat back or base portion 10, having side portions 11 and 12 bent forwardly therefrom and projecting upwardly, said upwardly projecting portions extending at an incline forwardly 80 of the back portion and having their forward edges inclined downwardly to the lower edge of the back portion. A pivot 85 bar 13 is formed integrally with the side portions, preferably extending between the upper ends thereof at the inner side forming bearing portions *a—a* adjacent said sides, and being disposed in spaced and parallel 90 relation with the upper edge of the back portion to form a slot 14.

The bar portion is preferably grooved longitudinally at its forward side throughout its length, to impart a semi-circular cross 95 section thereto, for the purpose of strengthening it and to provide an effectual pivotal bearing for the lever member which is hinged thereto, as will hereinafter more fully appear.

Adjacent its bottom edge the back portion 10 is provided with a series of separately cut spaced apart teeth 15, preferably arranged along the frame for approximately 105 its full width, and struck from said back to extend upwardly and forwardly therefrom, that is, to be situated upon the same side of the back as the side portions 11 and 12, the teeth being desirably of substantial V-shape as stamped from the V-shape openings 16 in the back.

The lever member consists of an operating

arm 17 and a clamping arm 18 disposed at an acute angle thereto, and having preferably a series of teeth or serrations 19 to engage and clamp the web, the bend between 5 the two arms being rounded in a manner as to rotatably engage the bar 13. The serrated portion of the clamping arm terminates in spaced relation to the ends of the member, and adjacent each end, and 10 spaced from the serrated portion by notches 20 and 21, there are provided ears 22 and 23, which in assembling are curled about the bearing portions *a—a* of the bar 13 to hingedly connect the lever member to the 15 frame member.

The clamping arm of the lever member is of less width than the slot 14, of the frame member, so that it may be rotated through the slot from the front to the rear side with 20 the serrations in spaced relation to the upper edge of the back 10. The forwardly offset relation of the bar 13 with respect to the back permits the clamping arm to assume a position within the slot 14 as shown in Fig. 25 7, in which the arm is substantially flush and in the plane of the back 10, so that a smooth flat rear surface is provided, and a relatively thin compact buckle is produced. The side portions 11 and 12 integrally supporting the bearing bar 13 furthermore produce an outer side surface entirely free of any projections, sharp points, or moving parts.

In assembling the web 24 with the buckle, 35 the end of the web is passed downwardly in front of the frame member and in the rear of the lever member and inserted between the teeth 15 and the back 10, the teeth being thereupon swedged back toward the openings 16 to securely grip the web. The web is then extended upwardly and over to engage the upper edge of the back 10, and is extended downwardly across the rear face of the frame member, and below said face 40 to produce the lower reach or loop for holding the usual cast-off 25. That portion of the web which is to comprise the upper reach of the web is passed upwardly in front of the frame member and in the rear of the lever member, the lever member being arranged, as shown in dotted lines in Fig. 3, 45 in the open position. After the upper reach or running portion of the web has been adjusted in an obvious manner to the desired position, the operating arm of the lever member is pressed to the closed position, as shown in Figs. 1 to 3, so that the serrated edge of the clamping arm presses the web through the slot 14 over the upper edge 50 of the covered back 10, the serrations being slightly to the rear of said upper edge so that the web is firmly clamped. The web being clamped by the engaging edge of the clamping arm and against the end portion 55 of the web covering the edge of the back in

a manner to effectually lock the lever member in closed position, so that it will not become disengaged of its own accord, but only by manually rotating the operating arm, and any pull on the web will tend to more firmly secure the same and hold the buckle closed.

The assembled web and buckle present a smooth relatively flat structure, free of any projections or surfaces which might tear 75 or abrade the clothing of the user, and the same may be worn with maximum comfort and convenience.

I have illustrated and described a preferred and satisfactory embodiment of the 80 invention, but it will be obvious that changes may be made therein, within the spirit and scope thereof, as defined in the appended claims.

Having thus described my invention, what 85 I claim and desire to secure by Letters Patent is:

1. A buckle comprising a sheet metal frame member and a lever member, hingedly connected thereto, said frame member including a back having integral web fastening means for securing the end portion of a web thereto, side portions extending above said back, a longitudinal bar formed integral with the back and in spaced relation 90 thereon forming a slot, said bar having a longitudinal groove pressed therein to impart a substantially semi-circular cross section thereto and being forwardly off-set from said back. 100

2. A buckle comprising a sheet metal frame member including a back, having a series of teeth cut and disposed forward from said back for the attachment of the end of a piece of web, side portions extending above said back, an integral pivotal bar 105 extending between said side portions in parallel spaced relation to said back to form a slot and being forwardly offset from said back, and a lever member hingedly mounted 110 on said bar and including an operating arm and a clamping arm, said clamping arm adapted to swing through said slot and to co-operate with the top edge of the back to clamp a web therebetween. 115

3. In combination, a buckle comprising a frame member including a back, side portions bent forwardly from said back and extending above the same, a bar formed integral with the upper ends of said side portions and extending between them in parallel spaced relation to said back to form a slot, and integral web fastening means on said back at the forward side thereof, a lever member pivotally mounted on said bar 120 between said side portions and including an operating arm and a clamping arm adapted to swing through said slot with its clamping edge in spaced relation to the upper edge of said back, and a web co-oper- 125 130

ating with said frame and lever members, said web fastening means of said frame member adapted to secure the end of the web at the forward side of said back in a manner to extend upwardly from said fastening means over the upper edge of said back rearwardly through said slot and downwardly across and against the rear face of said back, and continuing to form a loop, and finally extending upwardly across and in contact with said before mentioned end portion of the web and rearwardly and upwardly through said slot over the portion of the web engaging the upper edge of the back, and adapted to be engaged by the clamping arm of the lever member to clampingly press the same against the portion of the web extending over the upper edge of said back portion of the frame member.

4. In combination, a buckle comprising a frame member including a back, side portions bent forwardly from said back and extending above the same, a bar formed integral with the upper ends of said side portions, disposed in forwardly offset relation to said back and extending between said side portions in parallel spaced relation to said back to form a slot, and integral web fastening means on said back at the forward side thereof, a lever member pivotally mounted on said bar between said side portions and including an operating arm and a clamping arm adapted to swing through said slot with its clamping edge in spaced relation to the upper edge of said back, and a web cooperating with said frame and lever members, said web fastening means of said frame member adapted to secure the end of the web at the forward side of said back in a manner to extend upwardly from said fastening means over the upper edge of said back rearwardly through said slot and downwardly across and against the rear face of said back, and continuing to form a loop, and finally extending upwardly across and in contact with said before mentioned end portion of the web and rearwardly and upwardly through said slot over the portion of the web engaging the upper edge of the back, and adapted to be engaged by the clamping arm of the lever member to clampingly press the same against the portion of the web extending over the upper edge of said back portion of the frame member.

5. A buckle comprising a sheet metal frame member, said frame member including a back having a series of separate teeth cut and disposed outwardly and upwardly from said back for the attachment of the end of a piece of web, side portions extending above said back, integral pivotal portions connecting said side portions in parallel spaced relation to said back and being forwardly off-set from said back, and a lever member hingedly mounted on said pivotal portions and including an operating arm and a clamping arm, said clamping arm adapted to co-operate with the back to clamp a web therebetween.

6. A buckle comprising a sheet metal frame member, said frame member including a back having a series of teeth cut and disposed outwardly and upwardly from said back for the attachment of the end of a piece of web, side portions extending above said back, aligned bearing portions integral with said side portions in parallel spaced relation to the upper edge of said back and being forwardly off-set from said back, and a lever member hingedly mounted on said bearing portions and including an operating arm and a clamping arm, said clamping arm adapted to co-operate with the back to clamp a web therebetween.

5. In combination, a buckle comprising a frame member including a back, side portions bent forwardly from said back and extending above the same, a bar formed integral with the upper ends of said side portions and extending between them in parallel spaced relation to said back to form a slot, said bar having a longitudinal groove pressed therein to impart a substantially semi-circular cross section thereto, and in-

tegral web fastening means on said back at the forward side thereof, a lever member pivotally mounted on said bar between said side portions and including an operating arm and a clamping arm adapted to swing through said slot with its clamping edge in spaced relation to the upper edge of said back, and a web cooperating with said frame and lever members, said web fastening means of said frame member adapted to secure the end of the web at the forward side of said back in a manner to extend upwardly from said fastening means over the upper edge of said back rearwardly through said slot and downwardly across and against the rear face of said back, and continuing to form a loop, and finally extending upwardly across and in contact with said before mentioned end portion of the web and rearwardly and upwardly through said slot over the portion of the web engaging the upper edge of the back, and adapted to be engaged by the clamping arm of the lever member to clampingly press the same against the portion of the web extending over the upper edge of said back portion of the frame member.

6. A buckle comprising a sheet metal frame member, said frame member including a back having a series of separate teeth cut and disposed outwardly and upwardly from said back for the attachment of the end of a piece of web, side portions extending above said back, integral pivotal portions connecting said side portions in parallel spaced relation to said back and being forwardly off-set from said back, and a lever member hingedly mounted on said pivotal portions and including an operating arm and a clamping arm, said clamping arm adapted to co-operate with the back to clamp a web therebetween.

7. A buckle comprising a sheet metal frame member, said frame member including a back having a series of teeth cut and disposed outwardly and upwardly from said back for the attachment of the end of a piece of web, side portions extending above said back, aligned bearing portions integral with said side portions in parallel spaced relation to the upper edge of said back and being forwardly off-set from said back, and a lever member hingedly mounted on said bearing portions and including an operating arm and a clamping arm, said clamping arm adapted to co-operate with the back to clamp a web therebetween.

Signed at Bridgeport, in the county of Fairfield and State of Connecticut, this 31st day of Jan., A. D. 1924.

MICHAEL HAWIE.
